UNITED STATES PATENT OFFICE.

ALBERT G. THOMAS, OF PITTSBURGH, PENNSYLVANIA.

NEEDLE-VALVE FOR GAS-BURNERS.

1,027,934.

Specification of Letters Patent.

Patented May 28, 1912.

Application filed January 15, 1912. Serial No. 671,178.

To all whom it may concern:
Be it known that I, ALBERT G. THOMAS, a citizen of the United States of America, residing at Pittsburgh, in the county of Allegheny and State of Pennsylvania, have invented certain new and useful Improvements in Needle-Valves for Gas-Burners, of which the following is a specification, reference being had therein to the accompanying drawing.

This invention relates to needle valves for gas burners, and the primary object of my invention is to furnish a gas valve with a needle point that is arranged exteriorly of the same to avoid leakage of gas that has heretofore occurred by a needle point being located directly within the burner.

Another object of this invention is to provide a gas valve with a valvular member that is located to one side of the main gas passage of the valve, said member being operated by a stem that is removed to a point out of communication with the main gas passage of the valve to avoid leakage, the parts to the valve being more readily assembled and with a greater degree of accuracy.

A further object of this invention is to accomplish the above results by a mechanical construction that is simple, durable and highly efficient for the purposes for which it is intended.

With the above and other objects in view the invention resides in the novel construction, combination and arrangement of parts to be hereinafter specifically described and then claimed.

Reference will now be had to the drawing, wherein:—

Figure 1 is a side elevation of a gas valve in accordance with this invention, Fig. 2 is a plan of the same, Fig. 3 is a vertical sectional view of the valve, and Fig. 4 is a perspective view of the detached valvular member.

The reference numeral 1 denotes a cylindrical valve body having the lower end thereof provided with a socket 2, said socket having the walls thereof screw threaded to receive the exteriorly screw threaded end of a gas supply pipe (not shown). The upper end of the body 1 has a collar 3 and an exteriorly screw threaded nipple 4. The valve body 1 has a longitudinal central bore 5 in communication with the socket 2 and

in communication with a tapering or needle port 6.

The nipple 4 and the valve body 1, to one side of the bore 5 are provided with a longitudinal recess 7 having one end thereof closed and the opposite end open at the end of the nipple 4. The recess 7 is in communication with the transverse opening 8 formed in the collar 3, for a purpose that will presently appear.

Movably mounted in the recess 7 is a valvular member 9 having the outer end thereof provided with an inverted hook-shaped needle point 10 adapted to enter the port 6 and control the passage of gas through said port. The inner end of the valvular member 9 is cut away, as at 11 and provided with a transverse groove 12. Loosely engaging in the groove 12 is an eccentrically-disposed lug 13 carried by the inner end of a stem 14 that is revolvably mounted within the opening 8. The stem 14 has two spaced apart collars 15 and 16, the former being seated in the collar 3. Engaging the stem 14 between the collars 15 and 16 are the confronting ends of straps 17 secured to the collar 3 by screws 18 or other fastening means, said straps constituting means for retaining the stem 14 in engagement with the valve body 1. The outer end of the stem has a knurled wheel or handle 19 by which the stem is adjusted.

The cut away portion 11 of the valvular member 9 provides clearance for the inner end of the stem 14 and as said stem is rotated the valvular member 9 and hooked shaped metal point 10 are raised and lowered, consequently the supply of gas through the port 6 can be regulated from above and outside of the gas passage.

The arrangement of the valvular member 9 and the stem 14 does not weaken the construction of the valve body 1 and by not tapping into the bore 5, there is no liability of loss of gas due to a loose stem. This is an important advantage of my invention over the present type of needle valves, and while I have herein illustrated a preferred embodiment of the invention, it is to be understood that the structural elements are susceptible to such variations and modifications which will fall within the scope of the appended claims.

What I claim is:—

A regulating valve for gas burners com-

prising a valve body capable of communicating at one end with a gas supply pipe and having its other end formed with an outlet port, said valve body provided with 5 a recess independent of said port, a vertically movable valve for controlling the passage of gas through said port, a vertically movable actuating member mounted in said recess and carrying said valve and capable 10 of adjusting the latter, and means disposed

at right angles with respect to said recess and extending into said member for vertically moving it to adjust the valve.

In testimony whereof I affix my signature in the presence of two witnesses.

ALBERT G. THOMAS.
